UNITED STATES PATENT OFFICE.

ERICH BAUM AND MARTIN MUGDAN, OF NUERMBERG, GERMANY, ASSIGNEES TO CONSORTIUM FÜR ELEKTROCHEMISCHE INDUSTRIE G. M. B. H., OF NUERMBERG, GERMANY.

PROCESS OF PREPARING ACETALDEHYDE.

1,096,667.

Specification of Letters Patent.

Patented May 12, 1914.

No Drawing.

Application filed March 18, 1913. Serial No. 755,238.

To all whom it may concern:

Be it known that we, Dr. ERICH BAUM and Dr. MARTIN MUGDAN, subjects of the German Emperor, residing at Nuremberg, 5 Bavaria, Germany, have invented certain new and useful Improvements in Processes of Preparing Acetaldehyde, of which the following is a specification.

It has already been proposed to prepare 10 acetaldehyde from acetylene by the action of the latter upon a strong solution of sulfuric acid containing mercuric oxide (see for example Erdmann and Köthner, *Zeitschrift f. Anorg-Chemie* XVIII S. 55). Difficulty 15 has been experienced in working on these lines since a considerable part of the acetaldehyde which has been formed is transformed into condensation products (aldol, crotonic aldehyde, etc.) owing to the high 20 concentration of acid which was considered to be indispensable.

According to the present invention the absorption of acetylene and its transformation into acetaldehyde is effected in the presence 25 of oxide of mercury and sulfuric acid by limiting the acid content and by working at a temperature above the temperature of distillation of the acetaldehyde. It has been hitherto considered necessary in the 30 formation of acetaldehyde from acetylene, mercuric oxide and sulfuric acid to make a large addition of acid. The present invention depends on the contrary on the fact that the amount of acid should only be such that 35 the total quantity in the reaction liquid should be at most 60 grs. SO_4 per 1000 grs. water. Thus in the present process it is essential to limit the amount of SO_4 to at most 60 grs. SO_4 per liter and moreover to 40 operate at a temperature at which the aldehyde which is formed is evolved in the state of vapor. In this way a smooth formation of the acetaldehyde is attained and at the same time the recovery of the mercury which 45 has separated out in the process is facilitated to an extraordinary extent. The formation of condensation and transformation products of acetaldehyde is almost entirely avoided. The mercury collects at the bottom 50 of the reaction vessel in the form of a metallic regulus and when this has been oxidized it can readily be introduced into the process again in an economical manner, whereas in the known process in which large

quantities of acid are used and especially 55 when heat is employed, the mercury is obtained in the form of an impure emulsion which is difficult and unprofitable to treat further.

In French Patent No. 425057, which describes a process of obtaining aldehyde from acetylene by the aid of a mercury salt, a general remark has been made that in the preparation of acetaldehyde from acetylene by means of solutions of mercury salts and 60 sulfuric acid, the concentration of the sulfuric acid and the temperature of reaction are dependent on one another in such manner that lower temperatures should be employed at higher concentration and the reverse. It is further suggested when using 65 20% sulfuric acid the introduction of acetylene takes place at 40° and the aldehyde which is formed is distilled off at about 70°. The only example given in the French patent 70 for working with dilute acid (example 3 page 3) is one in which 25% acid is used at 40 to 45°, and the isolation of the aldehyde which is formed must then be effected by laborious distillation *in vacuo*. Thus it 75 is not possible either under these conditions or when using 20% acid to introduce acetylene continuously in the manner prescribed by us, whereby we obtain pure aldehyde forthwith in the distillate with simultaneous 80 formation of clean mercury, and without the formation of by-products. Thus from the results given in the French patent it could not have been foreseen that it is possible at the much lower concentrations 85 chosen by us (at most 60 grams SO_4 per 1000 grams of water) to introduce acetylene continuously and to distil off very pure aldehyde without further complications, and also to obtain the mercury again as a clean 90 metallic regulus, thus making an important 95 advance beyond the process given in this patent.

Example: 1750 grams mercuric oxide are added to 24 liters 3½% sulfuric acid and 100 acetylene is introduced with vigorous stirring and with heating to about 70 to 80°. Within thirty hours 5 to 6 kilograms of almost pure acetaldehyde condense in the worm condenser connected with the reaction 105 apparatus, the yield being almost theoretical calculated on the acetylene. The mercury is found at the end at the bottom of

the liquid as a clean metallic regulus. The liquid is almost water-clear and free from resin and dissolved mercury.

The mercury may be transformed again into mercuric sulfate by dissolving in concentrated sulfuric acid with heating, and again employed as catalyst. However, in this method of regenerating the catalyst, large quantities of sulfuric acid will be consumed and thus the operation would be tedious and unpleasant, owing to the evolution of sulfur di-oxid. We overcome this difficulty by oxidizing the mercury electrolytically. For this purpose we employ for instance an alkaline electrolyte and we may use with advantage a low percentage solution of caustic soda beneath which the mercury is placed as anode, while the cathode placed thereover is conveniently of iron and provided with openings for leading off the hydrogen. The mercury anode then soon becomes covered with a dark coating of mercurous oxid, which is to be continuously removed during the electrolysis by raking or by blowing electrolyte thereon or in any other suitable manner, in order to obtain favorable conditions of potential. The mercurous oxid so obtained which still contains metallic mercury and mercuric oxide is treated with a dilute sulfuric acid solution containing less than about 60 grams SO_4 per liter and again treated with acetylene while hot. The fact that in this method of working only mercurous salt is present from the beginning, possibly in presence of metallic mercury, in no way influences the course of the reaction. However, it is known to transform mercury into mercuric oxide or sulfate by the electrolytic method (cf., for example British Patent No. 28400 of 1903, and Severin *Toute la Chimie Minerale par l'Électricité*, 1908, page 645). This reaction has hitherto found no application in connection with the preparation of acetaldehyde from acetylene. It could not have been foretold that the product of electrolysis mainly consisting of mercurous oxid or of mercuric oxide with metallic mercury, which on solution in sulfuric acid is transformed to mercurous sulfate wholly or to a very large extent, could be employed in the present process and that indeed the mercurous compound is almost entirely as effective for the hydration of the acetylene as the equivalent quantity of mercuric salt.

The employment of the electrolytic regeneration of the oxid of mercury employed in combination with the present process of preparing aldehyde creates a cyclic process and thereby considerably increases the technical value of this method of preparing aldehyde.

In the claims we shall use the words "sulfate of mercury" as including either mercuric sulfate or mercurous sulfate or a mixture of both or a body obtained by treating mercuric oxid or mercurous oxid or a mixture of both, with sulfuric acid.

We declare that what we claim is:—

1. The process for the manufacture of acetaldehyde which comprises causing acetylene to interact with a solution of sulfuric acid containing sulfate of mercury as catalyst at a temperature at which acetaldehyde distils from said solution and at a concentration of acid not higher than 6%. 75

2. The process for the manufacture of acetaldehyde which comprises causing acetylene to interact with a solution of sulfuric acid containing sulfate of mercury as catalyst at a temperature 70-80° C. and at a concentration of acid not higher than 6%. 80

3. The process for the manufacture of acetaldehyde which comprises continuously causing acetylene to interact with a solution of sulfate of mercury as catalyst and not more than 6% of sulfuric acid, and simultaneously distilling off the acetaldehyde thus formed. 85

4. The process for the manufacture of acetaldehyde which comprises causing acetylene to interact with a solution of sulfuric acid of a concentration not higher than 6% and containing sulfate of mercury as catalyst, and heating the solution to such a temperature that the acetaldehyde thus formed 95 distils off. 90

5. The process for the manufacture of acetaldehyde which comprises causing acetylene to interact with a solution of sulfuric acid containing mercurous sulfate as catalyst at a temperature at which acetaldehyde distils from said solution and at a concentration of acid not higher than 6%. 100

6. The cyclic process for the manufacture of acetaldehyde which comprises causing acetylene to interact with a solution of sulfuric acid at a concentration not higher than 6%, containing a catalyst consisting substantially of mercurous sulfate at a temperature at which acetaldehyde distils from said solution, and re-oxidizing the mercury so formed by anodic oxidation introducing said oxidation product into sulfuric acid and again causing said solution to interact with acetylene. 110 115

In testimony whereof we affix our signatures in presence of two witnesses.
